(57) **CLAIM**

The ornamental design for a pin visor, as shown and described.

DESCRIPTION

FIG. 1 is a perspective view of a pin visor showing my new design;

FIG. 2 is a top elevational view thereof;

FIG. 3 is a front elevational view thereof;

FIG. 4 is a rear elevational view thereof;

FIG. 5 is a right elevational view thereof; and,

FIG. 6 is a left elevational view thereof.

The broken line shown on the pin visor represents stitching.
